B. A. MASON.

MACHINE FOR FORGING HORSESHOE NAILS, ALSO WROUGHT NAILS,
SPIKES, &c.

No. 22,663.

Patented Jan. 18, 1859.

UNITED STATES PATENT OFFICE.

BENJAMIN A. MASON, OF NEWPORT, RHODE ISLAND.

HORSESHOE-NAIL MACHINE.

Specification of Letters Patent No. 22,663, dated January 18, 1859.

To all whom it may concern:

Be it known that I, BENJAMIN A. MASON, of Newport, in the State of Rhode Island, have invented a new and useful Machine for

❶ Forging Horseshoe and other Nails, Spikes, and other Articles; and I do hereby declare that the following is a full, clear, and exact description thereof, reference being had to the accompanying drawings, making part of

❷ this specification, in which—

Figure 1, is a front elevation of the machine; Fig. 2, an end elevation; Figs. 3 and 4, vertical sections taken at the lines A, a and B, b, of Fig. 2; Fig. 5, is a plan of the bed of the machine; Figs. 6 and 7, face and edge view of one of the hammers; and Fig. 8, a separate view of one of the links with the india rubber bush.

The same letters indicate like parts in all

❸ the figures.

In the said machine the hammering of nails or other articles to be wrought is effected by four hammers arranged in two pairs, each pair moving in opposite directions to strike on opposite sides of the rod to be forged, and the other pair working in like manner, but the two pairs at right angles with each other and alternately, the faces of the four hammers being adapted to

❹ the form of the article to be forged. And another feature of the said invention relates to a method of relieving the hammers and their connections from the repeated shocks consequent upon the forging, and consists in

❺ the employment of vulcanized india rubber so interposed to receive the shocks at the moment of striking.

In the accompanying drawings there are three vertical and parallel plates (A, A', D,) which are suitably connected to form the frame of the machine. In each of the two plates (A, A') are formed two grooves (a, a,) crossing each other at right angles to form the ways or guides for four sliding hammers (B, B, B', B',) which all move toward and from a common center where the grooves cross. The faces of these hammers are to be suitably formed, swage like, to the form of nail, or other article to be forged

❻ by them, and they are operated by four cranks (e, e, e, e) one for each. The crank pins project from the face of four pinion wheels (H, H, H, H,) arranged at equal distances apart and around a master cog wheel

❼ H',) from which they all derive motion, the said master wheel being mounted on the

main shaft (R,) which has its bearings in suitable boxes in the two plates (A, A') its axes being in line with the central point of the crossing of the grooves (a, a,) in the 60 two plates.

Each hammer is connected with its appropriate crank pin by a joint link (f) the pin which connects the hammer with its link (f) passing through a bushing of vulcanized 65 india rubber, the elasticity of which will yield slightly to the shock when the hammer strikes the article that is being forged, thereby saving much of the wear and tear which would be consequent upon the hammering 70 operation. The four cranks are so placed as to move the two hammers (B, B,) which are in line, toward each other to strike the rod which is being forged on two opposite sides, while the other two hammers (B', B',) are 75 moving from each other, and after striking they (the hammers B, B,) are moved from each other to return while the other two (B', B',) are moved toward each other to strike the other two faces of the rod.

The hammers are formed with a fillet (K,) on each of the two opposite edges fitted to the guide or way grooves in the plates as before described, but they may be guided in any other equivalent manner.

In front of the plate (A') there is a bracket piece (2) with a guide hole through which the operative introduces that end of the rod which is to be forged, and this retains it centrally between the four hammers which act upon its four faces to reduce it to the form required. If the articles to be forged are nails, as soon as the end of the rod is reduced and forged to the required form of the under part of the head, the shank and point, the rod is drawn out and inserted to the distance required through a hole (d) in the front plate (A'). The lower part of this hole is formed to be a stationary shear cutter, and against the inner face of the plate (A') is mounted a rotating shear (c) mounted on a shaft (c') which receives motion from the master wheel by a pinion (s) and by the rotation of the shear (c) the nail is cut off and drops through a hole (F) in the platform (E), and the rod is returned to the hammers to forge another nail. Instead of the rotary shear any other suitable shear may be substituted.

From the foregoing it will be seen that by giving the required form to the face of the hammers various articles may be forged,

although my said invention is chiefly intended for forging horse shoe and other nails, and for the forging of nails I prefer to form the face of each hammer with a cavity having a shoulder each side as represented in Fig. 7, the article to be forged being formed between the said shoulders, thus giving the required form to the nails at the angles.

10 What I claim as my invention and desire to secure by Letters Patent is—

1. The combination of the four hammers arranged in pairs, the two constituting each

pair being mounted to strike simultaneously and in opposite directions, and the two pairs 15 working at right angles with each other or nearly so, substantially as described, and for the purpose set forth.

2. The employment of an elastic bush in the connection of the hammers with the 20 cranks by which they are operated, substantially as and for the purpose set forth.

BENJ. A. MASON.
